UNITED STATES PATENT OFFICE

2,010,999

CAM FEED DRILLING HEAD

Edward Joslin Kingsbury, Keene, N. H., assignor
to Kingsbury Machine Tool Corporation, Keene,
N. H., a corporation of New Hampshire

Application September 19, 1932, Serial No. 633,888

10 Claims. (Cl. 77—33)

This invention relates to machine tool units of the drill type, and more particularly concerns an automatic or semi-automatic unit having a self-contained power plant and means for rotating and for feeding a tool head.

One of the features of the present invention is the provision of such unit with cam feeding mechanism controlled through a power transmission including a single cam element for controlling the feed of the tool, along with automatic means for controlling the feeding of the tool by said cam.

Another feature of the present invention is the provision of such a unit with a vertical drive shaft whereby the driving motor may be located above the unit, and coupled thereto by a belt drive so that the speeds may be varied, with constant motor speed, by simple interchange of pulleys, and without requiring a large space for the reception of the parts.

A further feature of the invention is the provision of a simple and direct screw adjustment for the position of the general housing with respect to the work, for determining the position of the tool in its feeding movement.

Still another feature of the invention is the provision of a tapered gib construction in conjunction with means mounted on the housing proper for moving the gib whereby to clamp or release the housing for adjustment; and affording when engaged a clamping of the housing for substantially its entire length.

A still further feature of the application is the provision for electrical controls for interlocking or synchronizing the several units which constitute a complete machine.

Other features of the present invention, including the assemblage of the several parts, are set forth on the accompanying drawings which illustrate one form of construction of the device according to the present invention, and in which:

Figure 1 is a side elevation of the unit including the mechanism housing, the motor bracket, the motor and the motor drive system.

Figures 1a and 1b are respectively a side elevation and a top plan view of the mechanism housing, with a modified form of motor bracket.

Figure 2 is a front elevation on a larger scale, of the mechanism housing.

Figure 3 is a plan view of the housing, with the cover and drive pulley removed.

Figure 4 is a horizontal section substantially on line 4—4 of Figure 2 showing the housing in bottom plan.

Figure 5 is a side elevation of the housing, with

a side plate removed to reveal the cam member.

Figure 6 is a cross sectional view, on a larger scale, substantially on line 6—6 of Figure 5.

Figure 7 is a side elevation, from the side opposite that of Figure 5, with the side plate removed.

Figure 8 is a transverse vertical sectional view substantially on line 8—8 of Figure 5.

Figure 9 is a vertical sectional view through the drive shaft and the spindle, substantially on line 9—9 of Figure 10.

Figure 10 is a vertical transverse sectional view substantially on line 10—10 of Figure 9.

Figure 11 is a similar sectional view substantially on line 11—11 of Figure 9.

Figure 12 is a transverse sectional view substantially on line 12—12 of Figure 9.

Figure 13 is a transverse vertical sectional view substantially on line 13—13 of Figure 9.

Figure 14 is a detail sectional view substantially on line 14—14 of Figure 7.

Figure 15 is a circuit diagram.

In the drawings, the unit is illustrated as comprising a general housing H having a drill spindle extending from one end thereof, and provided at its top with a sliding motor bracket B having a vertical support for the self-contained driving motor M which is mounted with its shaft vertical and provided at its lower end with a pulley 10 operating by V-belts 11 to drive the pulley 12 on the vertical main drive shaft 13. The main drive shaft 13 extends vertically downward in the housing H and is provided with bearings 14 supported by this housing. A bevel gear 15 on drive shaft 13 meshes with bevel gear teeth 16 on a hollow shaft 17 supported by bearings 18 on a cross web of the housing H. The hollow shaft 17 has the worm 19 thereon in mesh with the worm wheel 20 of a first cross shaft 21 and is provided internally with axial teeth 22 in mesh with the teeth of a spindle 23 rotatably mounted by bearings 24, 25 in a non-rotatable but axially movable quill 26 having a rack 27 formed thereon for engagement by the teeth of a gear 28 mounted on a second transverse shaft 29. The outer end of the spindle 23 is provided with a tool-holding clutch assembly 30 of any desired type. An oil and dust-tight seal 31 is preferably provided around the quill 26. Thus, when the motor M turns, the main drive shaft 13, the hollow shaft 17 and the spindle 23 are driven in rotation so that a drill is rotated for cutting.

The transverse shaft 21 is turned at the same time, this shaft (Fig. 10) being provided at one end with a gear 32 which meshes with a large gear 33 (Fig. 7) fixed to a small gear 34 which

55

in turn is in mesh with a large gear 35 on a third transverse shaft 36 having axial teeth 37 thereon for engagement in internal teeth of a clutch collar 38 which may slide along the length 5 of shaft 36 but is connected for positive angular movement therewith. The end 36a of shaft 36 extends into a hollow clutch shaft 39 which is co-axial therewith and has, at its inner end, clutch teeth 40 for engagement by corresponding teeth on the clutch collar 38, so that shafts 36 and 39 may be coupled together at times determined by the action of the clutch actuating arm 41 which is fixed to the upper control rock shaft 42 (Figs. 9, 10 and 11). Clutch shaft 39 has 10 teeth 43 (Figs. 5 and 10) which mesh with the peripheral teeth of the cam wheel 44 mounted on the fourth transverse shaft 44a and having a single cam track 45 (Figs. 5 and 12) cut on its inner face for engagement with the roller 46 15 mounted on a stub 47 of the rocker arm 48 carried by a transverse pivot 49 and having peripheral rack teeth 50 at its outer end for engagement with a gear 51 mounted on the second transverse shaft 29.

25 The second transverse shaft 29 carries at its end a limit disk 52 (Figs. 7 and 13) having a pair of stub buttons 53, 54 thereon for cooperation with the lever 55 which actuates the plunger 56 of a circuit closing device 57, shown in detail 30 in Figure 14, and a rock shaft link 76.

This circuit closing device includes an axially movable sleeve 58 which is forced toward the right by a strong spring 59 and thus held in a right hand limit position. An insulating piece 35 60 has a pair of contact pieces 61 which are connected to conductors 62, 63, and extend through the insulation piece to position opposite a circuit closing bridge 64 carried by a stud 65 moved by the plunger 56. This plunger is normally urged toward the right in Figure 14 by a spring 66 so that it removes the bridge 64 out of engagement with contacts 61, as shown in Figure 14. It is preferred to form the plunger 56 as a separate element from an insulated inner 40 end 67 carrying the stud 65, and a separate spring 68 is then provided for the main portion of the plunger. The bridge 64 is movable along the length of stud 65, but is forced toward the left in Figure 14 by a light contact-maintaining spring 69. This entire assemblage is located 45 within a hole in the housing, and is held in position by a fitted ring 70 and the closing plug 71. In operation, as the lever 55 presses the plunger 56 toward the left in Figure 14, the springs 66, 50 68 yield and the bridge 64 closes a circuit across the contacts 61. Further movement of the lever 55 causes a compression of spring 69, until ultimately the compression forces so transmitted are sufficient to cause movement of the sleeve 58 and 55 compression of the stronger spring 59, but all the while contact is maintained.

The control rock shaft 42 has a rocker arm 75 (Figs. 7, 9 and 11) pivotally connected at its swinging end to a downwardly extending link 65 76 which is forced outwardly at its own lower end by a compression spring 77; the assembly of rocker 75 and link 76 being constantly pressed downward (Fig. 11) by an adjustable spring 78 (Fig. 11).

70 A manually depressible plunger 79 extends horizontally in the housing and, having an inner end of magnetic material, may be drawn inwardly by a solenoid 80 fixed in the housing, against the action of a return spring 81. The plunger 75 79 has a pin 82 to limit its outward movement.

The stud 54 on limit disk 52 may engage with the lower end of link 76 during the clockwise movement thereof (Fig. 7), which corresponds to a withdrawal of the tool from the work, and thereby raise link 76 and rock shaft 42 until the clutch teeth 40 are disengaged, against the action of spring 78. Energization of plunger 79, however, causes pin 82 to engage the lower end of link 76 and causes it to rock clockwise (Fig. 11) against the action of spring 77, until it slips from the end of stud 54, and is thereupon forced downward by the spring 78 to effect engagement of the clutch teeth 40. Obviously, the same operation may be accomplished by manual pressure on the projecting end of plunger 79. 15

The structure is enclosed by a right hand side plate 99 and a left hand side plate 91, to protect the several gears and parts; and it is preferred to form a chamber 93 in the base as an oil reservoir, from which oil may be forced by any suitable means (not shown) into ducts 95, 96 (Fig. 9) to various operating parts and basins so that the entire system may be properly lubricated, with a drainage back into the sump chamber 93. 20

The housing H is slidably mounted in ways on a bed K (Figs. 1 and 2) and, as shown in Figures 2 and 4, one side of the housing H is provided with an inclined surface 100 which cooperates with a correspondingly tapered gib 101 in the ways in bed K. A vertically disposed shaft 102 in the housing is provided at its lower end with teeth engaging in teeth 103 in gib 101 so that, by rotation of the shaft, the gib may be moved to release or to clamp the housing in fixed position with respect to the bed K. The shaft 102 passes upwardly through the housing and extends into a recess 104 (Figs. 3 and 7) and is provided with a hand lever 105 by which it may be moved to cause the aforesaid linear movement of the gib. A spring pressed plunger 106 is illustrated for maintaining the handle 105 in either end position.

A longitudinal adjustment head 110 is fixedly connected to the bed K and is provided with an outer thrust bearing 111 for a threaded spindle 112 which extends through an oil and dust-tight packed opening into the housing H (Fig. 9) and threadedly engages a lug 113 having a horizontal threaded aperture. Within the adjustment head 110 is provided a worm wheel 114 50 fixed to the end of spindle 112 and in engagement with a worm 115 on an angularly inclined transverse shaft 116 (Figs. 3, 8 and 9) provided at its upper end with means for engagement by a handle 117. It will be noted that the transverse shaft 116 is located below and adjacent the position of the chuck 30 so that it is immediately accessible by an operator, and at the same time is removed from interference with the operation of the tool. 55

In operation, with the quill 26 in withdrawn position, i. e. at a left hand position in Figure 9, the rotation of the motor drives the pulley 12 and shaft 13 and by gears 15, 16 causes rotation of hollow shaft 17 and therewith of the drill 65 spindle 23 and the chuck 30.

At the same time, the worm 19 rotates gear 20 and shaft 21 so that shaft 36 is turned. Stub 53 is now holding (Fig. 7) the lever 55 for the engagement of bridge 64 with contact 61. If 70 switch 121 is closed, the solenoid 80 is energized, and plunger 79 is drawn inward to remove link 76 from stub 54, so that the link moves downward under the urgency of spring 78, and rock shaft 42 turns in a clockwise direction (Figs. 75

10 and 11) and the clutch teeth 40 engage with the teeth on clutch collar 38. Shaft 36 thus drives the hollow shaft 39 and causes a rotation of the cam disk 44 so that its track 45 causes 5 a single rocking movement of the rock lever 48. The teeth 50 of this rock lever rotate gear 51 (Fig. 5, clockwise) and thus rotate shaft 29 and gear 28 (Fig. 9, clockwise), and the quill 26 is forced toward the right in Figure 9, with a feeding 10 movement of the tool at a rate controlled by the speed of the motor and by the shape of the cam track 45. Drilling is thus accomplished.

During the initial movement of shaft 29, stub 53 withdraws from lever 55 and the bridge 64 may retreat from contact 61 and thus open the solenoid circuit, so that the plunger 19 is released and moves back into the position shown in Figure 11, by the action of a spring 81. The continued movement of disk 52 also results in 20 a downward or counterclockwise movement of stub 54 (Fig. 7) with respect to the lower end of the link 76, until ultimately this link is snapped back to a position above stub 54 by the action of spring 71.

25 At the completion of the drilling or similar operation, the shape of the cam track 45 causes a reverse movement of the rock lever 48 and therewith a counter-clockwise movement of gear 51 (Fig. 5) and a counter-clockwise movement of gear 28 (Fig. 9) so that the quill 26 and the chuck 30 are withdrawn from the work. Toward the end of this reverse rotation of shaft 29, the disk 52 begins raising the link 76, and this movement continues until rock shaft 42 has 35 been moved to disengage the clutch collar 38 from the teeth 40: the feeding of the tool is thus interrupted. If the switch 122 is held closed, stub 53 moves lever 55 and again closes the circuit by bridge 64 so that the above feeding movement is repeated, and will be repeated so long 40 as switch 121 remains closed.

If switch 121 is momentarily closed to initiate the movement, the quill 26 is fed forward and then withdrawn once only.

45 It will be noted also that the device may be set in motion manually by depressing the plunger 19 even though current is not being supplied through conductors 120 and switch 121.

While any desired type of tool chuck 30 may 50 be employed, a preferred form is shown in Figures 3, 5, 6 and 9 as comprising an external sleeve 130 having an external thread 131 to receive an external nut 132 which is cut away (Figs. 3 and 5) to reveal the graduations 133 55 on the end of the external sleeve 130. An internal member 134 to receive the drill or like shank is provided with threads at its ends to engage an internal nut 135 having micrometric indications 136 (Fig. 3) thereon for reading in conjunction with the indications 133. This arrangement cooperates with the aforesaid construction of the housing and bed for attaining a very close adjustment of the working of the tool and its position at the limit of the forward 60 movement of the quill 26.

In Figure 15 the supply conductors 120 may 65 supply current through branch conductors 121 and a manually closable switch 122 to the solenoids 80 of three units R, S, T, in multiple, so that these solenoids are operated together when the switch 122 is closed. These units are provided with the individual quills 26 each having a drill spindle and drill, in this illustrated form, for operating upon a piece of work W held between a fixed clamp piece 123 and a movable

clamp piece 124 which may be engaged tightly with the work by a rotatable clamping cam 125 having a shoulder thereon for engagement by the locking plunger 126, so that the work, when clamped, is latched against release so long as the plunger 126 is held against the cam shoulder by its spring 127. That is, when the switch 122 is closed, each unit operates for its individual operation, and then returns to its withdrawn position. Under these conditions, as described above, the 10 bridge 64 of each unit engages the contacts 61 of the unit to close a circuit between the contacts. A conductor 128 extends from one main conductor 120 to one terminal of the closing switch of the unit T, a conductor 128 connects the other terminal of this closing switch with one terminal of the closing switch in unit S, a conductor 130 connects the other terminal of the closing switch in unit S to one terminal of the closing switch in unit R, and a return conductor 131 joins the other terminal of the closing switch of the unit R with the solenoid 132 and thus back to the other main conductor 120. Since the closing switches of the units T, S, R are joined in series by these conductors, the circuit is not energized until all units 25 have returned to the withdrawn position, i. e. until they have finished their individual operations. When this has occurred, the solenoid 132 is energized and its bridge 133 closes a circuit by conductor 134 through the solenoid 135 and by 30 conductors 136 and 137 back to the other main conductor 120. Solenoid 135 then operates to withdraw the plunger 126 so that the cam 125 is released, and the work clamps 124, 123 may be separated to release the work W. This construction, therefore, permits an interlocking of the several units, so that their operations may begin at the same time, and so that an auxiliary operation cannot be initiated until each of the working units has reached a predetermined position. 40

In the form of construction shown in Figures 1a and 1b the motor bracket has been modified so that the motor is supported at the rear of the housing instead of at the top thereof. The housing H is provided as before with upstanding bolts 45 143 which pass through slots in the horizontal portion 141 of the motor bracket, this horizontal portion being provided with downwardly extending lateral portions 142 cooperative with the top of the housing to permit a sliding movement of the 50 motor and its shaft whereby to adjust the tension of the driving belts. This motion may be produced, and limited by a regulating screw 143 which acts to force the motor bracket toward the left as it is screwed in, and thus to tighten the 55 belts. The horizontal portion 141 is integral with spaced downwardly extending legs 144, having a web plate 145 between them for supporting the motor M. Likewise integral with the portion 141, 60 143 of the motor bracket is a guard 146 which extends over the motor pulley 10 and the unit pulley 14.

By this modified construction, the height of the entire structure is reduced, but the horizontal extension in length is increased. In each construction, the motor is supported adjustably upon the housing itself, and moves to and fro with the housing, so that adjustments accomplished through the spindle 112 do not affect the tension 70 of the driving belt.

It is obvious that the invention may be modified in many ways without departing from the scope of the appended claims.

Having thus described the invention, what I 75

claim as new and desire to secure by Letters Patent, is:—

1. In an apparatus of the class described, a drill spindle and a driving device therefor, a first shaft having thereon means for moving the spindle back and forth according to the direction and amount of movement of said first shaft; means for turning said first shaft cyclically first in one direction and then the other and including a pinion on said shaft, a rack for moving said pinion, a rotatable cam for moving said rack, a disconnecting clutch, and a source of power operative through said clutch to rotate said cam; a rocker member operatively connected for engaging and disengaging said clutch, an abutment carried by said first shaft, means operated by said abutment when the first shaft moves the spindle into withdrawn position for moving the rocker member to disengage the clutch whereby to terminate a cycle, said moving means including a manually movable part operative when moved for separating said abutment and abutment-operated means, and a spring for moving said rocker member to engage said clutch whereby to start a new cycle when said part has been moved to interrupt such operative relation.

2. In a device of the class described, a drill spindle and a driving device therefor, a first shaft having thereon means for moving the spindle back and forth according to the direction and amount of its own movement, an eccentric device mounted on said first shaft, a second shaft, a cam rotated by said second shaft, means moved by said cam for turning said first shaft cyclically first in one direction and then the other, a first clutch element connected to said second shaft, a second clutch element movable relative to said first clutch element, means for rotating said second clutch element in one direction, a rock shaft having fixed thereto a device operative for engaging and disengaging said clutch elements, means operated by said eccentric device when the spindle moves into withdrawn position for moving said rock shaft to disengage said clutch elements, manually movable means operable to dislodge the said disengaging means from said eccentric device, and a spring for moving said rock shaft for engaging said clutch elements upon such dislodgment.

3. In an apparatus of the class described, a drill spindle and a driving device therefor, a first shaft having thereon means for moving the spindle back and forth according to the direction and amount of movement of said first shaft, a cam, devices moved by said cam for turning said first shaft cyclically first in one direction and then the other, a source of power, a disconnecting clutch for coupling said source for rotating said cam, a rocker member operatively connected for engaging and disengaging said clutch, an abutment carried by said first shaft, a link pivoted eccentrically on said rocker member and engaged and operated by said abutment when the first shaft moves the spindle into withdrawn position for moving the rocker member to disengage the clutch whereby to terminate a cycle, the pivotal connection of said link to said rocker member permitting the link to be swung out of the path of movement of said abutment, manually operable means for swinging the link out of said path, and a spring for moving said rocker member to engage said clutch whereby to start a new cycle when said link has been swung away from engagement with said abutment.

4. An apparatus as in claim 3, in which the pivotal connection of said rocker member is at

a right angle to the axis of said first shaft, and a spring is employed for pressing said link back into the path of said abutment when the said abutment has been returned by said first shaft during the forward movement of the spindle 5 which occurs during the new cycle.

5. An apparatus as in claim 1, including a manually slideable member operative for moving said part to dislodge it from said abutment, said sliding member including an externally projecting 10 end for manual operation, a solenoid for moving said slider to effect such dislodgment, and a spring for returning the slider.

6. A machine tool including a plurality of compact self-contained independently operated drilling units; each unit comprising a rotatable and translatable tool spindle, feeding means for advancing and retracting said spindle, a motor mounted with said drilling unit for rotating the spindle and operating said feeding means, a disconnecting clutch included in said feeding means, a control device for said clutch including spring means for engaging said clutch, an actuating link connection engageable and moved by the feeding means for disengaging said clutch and holding it 25 disengaged upon completion of a cycle of operations of said spindle, and a solenoid operative 30 upon the link connection for releasing the engagement of the same with the feeding means so that said spring means may re-engage said clutch to start a new cycle; and an electrical contactor and means supplied therethrough for energizing the solenoids of all said units simultaneously.

7. A compact self-contained drilling unit consisting of a frame with a flat base, a tool spindle mounted in the frame for rotation and for reciprocation parallel to the base, a driving device for rotating the spindle, means for feeding said spindle and including a rotatable cam mounted with its axis transverse to a plane intersecting the axis 40 of the spindle, transmission devices connecting said cam with said driving device and including a shaft parallel to the axis of the cam, a disconnecting clutch on said shaft, a spring for normally engaging said clutch, a rock shaft extending 45 substantially parallel to said spindle, an arm on said rock shaft for engaging and disengaging said clutch, a second arm on said rock shaft, a link pivoted to said second arm eccentric to the axis of said rock shaft, an abutment moved by said 50 cam and engageable with said link for operating the same positively to disengage said clutch and therewith terminate a cycle of movement of the spindle, a movable member operative for moving said link about its pivot connection with said second arm to dislodge the link from engagement with said abutment whereby to permit said spring 55 to re-engage the clutch to start a new cycle, said movable member including a portion accessible from the exterior of the frame for manual operation.

8. An apparatus as in claim 7, in which said portion operates as an external visual indicator of the position of said movable member, and a solenoid is located within the frame for moving 65 said movable member to effect such dislodgment, and in which a spring is provided for returning the movable member when the solenoid is disengaged.

9. A compact self-contained drilling unit 70 consisting of a frame having a flat base, a tool spindle mounted in said frame for rotation and for reciprocation parallel to said flat base, said frame having sides substantially parallel with said spindle, a driving device for said spindle, 75

feeding means for said spindle including a cam, transmission devices connecting said cam with said driving device and including a disengaging clutch, a rocker member operatively connected for engaging and disengaging said clutch, an abutment moved by said cam, means operated by said abutment upon the completion of a cycle of cam movement for positively moving the rocker member to disengage the clutch and including a part movable for interrupting the positive engagement between said abutment and the rocker member, a spring for moving said rocker member to engage said clutch whereby to start a new cycle when said part has been moved to interrupt such positive relation, a slidable member operative for moving said part out of its position of said positive connection between the abutment and the rocker member, a solenoid operative when energized from a remote point of control for moving said slidable member to cause said disengagement, and a spring for returning the slidable member when the solenoid is de-energized; all said driving, feeding, transmitting and controlling elements and means being located between the said parallel sides of said frame and enclosed thereby.

10. A machine tool comprising a frame, a rotatable and translatable tool spindle, a feeding mechanism including devices for cyclically advancing and retracting said spindle, said feeding mechanism including a source of power and a clutch which may be opened to stop the translational movement of said spindle, a spring for engaging said clutch, a member operative upon movement in one direction for opening said clutch, abutment means moved in unison with the spindle for engaging said member toward the end of the retracting movement of said spindle whereby to move it in said one direction for opening the clutch and terminating a working cycle, said member and abutment means co-operating to maintain said clutch in open position, said member being also movable in a direction at an angle to said first direction whereby to release the engagement between said member and said abutment means so that the spring may engage the clutch to start a new cycle, and means operating during the course of the cycle to restore said member to a position for again engaging said means to effect the termination of the new cycle. 20 25

EDWARD JOSLIN KINGSBURY. 25
